UNITED STATES PATENT OFFICE.

EDWIN MOORE, OF PHILADELPHIA, PENNSYLVANIA, ASSIGNOR TO MOORE PUSH-PIN COMPANY, OF PHILADELPHIA, PENNSYLVANIA, A CORPORATION OF PENNSYLVANIA.

HANGER.

1,049,128.

Specification of Letters Patent. Patented Dec. 31, 1912.

Application filed March 8, 1909. Serial No. 482,067.

To all whom it may concern:

Be it known that I, EDWIN MOORE, a citizen of the United States, residing in Philadelphia, Pennsylvania, have invented Im-
5 provements in Hangers, of which the following is a specification.

The object of my invention is to construct a hanger by which heavy articles, such as pictures and the like, can be sus-
10 pended from a wall; the hanger being carried by a comparatively light nail or brad. This object I attain in the following manner, reference being had to the accompany-
ing drawing, in which:—

15 Figure 1, is a sectional view of a lath and plastered wall showing my improved hanger in position; Fig. 2, is a detached perspective view of the hanger and the nail from which it is suspended; Fig. 3, is a front view; Figs. 4 and 5, are views of one modification of the invention; and Fig. 6, is a perspective view of another modification.

A is the hanger made, in the present instance, of sheet metal bent into shape, hav-
25 ing a hooked portion α at the lower end from which the picture or other article is hung. This hook is preferably curved trans-
versely, forming a slight stiffening rib as at α' . The flat body portion of the hanger is
30 twisted at α^2 to form two parts or sections at right angles to each other, and the ex-
treme upper end α^3 of one part is rolled up or turned over to form a channel α^4 inclined at an angle of less than 90° to the general
35 line of the hanger, for the reception of a nail B. As a consequence of this construc-
tion the nail placed in this channel may be driven at an angle of less than 90 degrees with the plane of the back face of the
40 hanger. The nail is preferably made of steel, having a sharp point b and a head b' of any form desired. The nail is compara-
tively small and is driven into the plaster and, by preference, a short distance into the
45 lath, as illustrated in Fig. 1, as it is essen-
tial that the point of the nail should be held so that when a weight is suspended from the hook of the hanger the hanger will have a
50 tendency to press firmly against the wall and the hold of the point of the nail will prevent any downward movement. The angle in which the nail is driven is such that there is no tendency of the nail to turn on its point and break or tear the plaster, and
55 the fastening will hold unless the weight is

sufficient to carry the entire nail and hanger bodily down with it, tearing the lath as well as the plaster or other intervening material. The inclined channel α^4 also acts as a guide in driving the nail, as the nail must be 60 driven at the proper angle, and this can be done by a person whether experienced or not in driving nails.

The hanger can be made of very light ma-
terial, as the part which receives the great-
est strain is directly under the channel α^4 ,
but at this point the metal is set on edge
and bent at the point α^2 to form the hook;
the hook being strengthened by shaping it
as above set forth. 70

In some instances the upper end which is
bent to form the channel α^4 may be secured
to the body of the hook by soldering, or a
tongue c may be formed on the end of the
body α' , as illustrated in Fig. 4, and passed
75 through an opening c' and riveted thereto,
as shown in Fig. 5, and in some instances a
sharp projection d may be formed at the
back of the hooked portion by punching out
80 the metal and bending it as illustrated in
Figs. 4 and 5, to prevent the hook swinging
when once in place.

Where a very heavy article is to be sus-
pended the hanger may be made as shown
in Fig. 6, the hanger A² in this instance
having two arms e, e, each of which termi-
nates in a channeled head e' arranged at an
angle similar to that in Fig. 1, and the
hooked portion of the hanger may be made
in the same manner as the hook α in Fig. 1. 90

It will be understood that the nail is pref-
erably made of steel and very sharp, conse-
quently it can be readily driven into the
plaster, wood or even into brick for a given
distance sufficient to allow the point to em-
bed itself to resist any downward pull due
to the weight of the object being hung on
the hanger, and a nail of this kind makes a
comparatively small hole and consequently
the plaster or paper is not disfigured, and
when the nail is drawn the hole is so small
as not to be perceptible to the casual ob-
server. 95

I claim:—

1. A hanger formed of a strip of substan-
tially flat material having a hook at one end
and bent to form a nail-receiving channel at
the other end, said strip being given a quar-
ter-twist to cause that portion of the strip
which includes and is adjacent the nail-re- 105

110

ceiving portion, to stand at right angles to the hook-containing portion and edgewise to the wall or supporting surface, the back of the hook and the back edge of the portion at right angles thereto being in the same plane to lie parallel with and against the wall or supporting surface.

2. A hanger having a flat body portion twisted to form two parts at right angles to each other and bent at its lower portion to form a hook, the upper end of the body having an opening and being shaped to form an inclined nail channel; said end having a tongue fitting said opening.

3. A hanger having three arms; the lower arm being in the form of a hook; the two side arms being each twisted to form two parts at right angles to the plane of the lower arm and the upper end of each side arm having an inclined passageway for the reception of a nail.

In testimony whereof, I have signed my name to this specification, in the presence of two subscribing witnesses.

EDWIN MOORE.
